UNITED STATES PATENT OFFICE.

GEORGE W. LEWIS, OF PERU, ILLINOIS, ASSIGNOR OF ONE-HALF TO
CHARLES BRUNNER, OF SAME PLACE.

GAS-ENGINE.

SPECIFICATION forming part of Letters Patent No. 451,621, dated May 5, 1891.

Application filed April 22, 1890. Serial No. 348,973. (No model.)

To all whom it may concern:

Be it known that I, GEORGE W. LEWIS, of Peru, in the county of La Salle and State of Illinois, have invented certain new and useful 5 Improvements in Gas-Engines; and I do hereby declare that the following is a full, clear, and exact description thereof, reference being had to the accompanying drawings, and to the letters of reference marked thereon, 10 which form a part of this specification.

This invention relates to that class of gas or gasoline engines in which but one impulse is made for every two revolutions and in which the power-cylinder is also utilized as an air- 15 pump, a separate air-pump being dispensed with.

Among the objects of the invention are the saving of power by the avoidance of air-compression on those strokes of the engine next 20 preceding the explosion, and also in the avoidance of waste of the vapor of gasoline or other volatile liquid employed for imparting combustible properties to the explosive compound.

25 It is also an object of the invention to provide a simple and inexpensive construction attaining the purposes above mentioned.

In the attainment of the first-mentioned object of my invention I provide for keeping 30 continuously open the exhaust pipe or passage leading from the power-cylinder during the time when the engine is running at excessive speed, which, of course, prevents idle compression of air on the back-stroke of the 35 piston.

The next mentioned object of the invention is in part attained by the same provision, since when the exhaust-pipe is held open during a forward movement of the piston 40 such forward movement of the piston will draw external air into the cylinder through the exhaust-passage, rather than through the air and gas supply pipe, and there will therefore be no waste of gas or vapor from its induction when not wanted for use; but in addition to the provision made for keeping the exhaust-passage open I also provide for stopping the pump by which gasoline or gas is injected into the air-pipe, and as a consequence 45 50 none is supplied except when it is required and can be utilized.

In the accompanying drawings, illustrating my invention, Figure 1 is a side elevation of the engine. Fig. 2 is a top or plan view. Fig. 3 is an end elevation. Fig. 4 is an enlarged 55 view of certain parts by vertical section in line 4 4 of Fig. 2. Fig. 5 is a detail seen in a section taken on line 5 5 of Fig. 4. Fig. 6 is a longitudinal section of the pump intended for gasoline or other suitable volatile liquid. 60 Fig. 7 is a horizontal section of the rear end of the cylinder and its ignition-chamber, taken on line 7 7 of Fig. 8. Fig. 8 is a vertical section of the same, taken on the line 8 8 of Fig. 7. The foregoing figures illustrate 65 the complete machine as adapted for the use of gasoline or other suitable volatile liquid. Figs. 9 and 10 illustrate modifications especially intended for use when illuminating or other suitable gas is employed instead of gasoline or similar liquid, Fig. 9 being a side elevation of certain parts seen in a section on line 9 9 of Fig. 10, which illustrates the same parts in top or plan view.

A represents the frame or bed of the machine; 75 B, the cylinder fixed to said bed and open at its front end, and C a crank-shaft operated from the piston within the cylinder B by means of the piston-rod C', and carrying a fly-wheel C² and belt-pulley C³.

At the rear end of the cylinder B is provided an ignition-chamber B', formed, as here illustrated, by a recessed head closing that end of said cylinder, as plainly indicated in Fig. 7. The mixed gas and air, or, in other words, the 85 explosive compound, is conducted into this ignition-chamber (which is in open communication with the interior of the cylinder B) through a pipe B², having a check-valve B³. (Seen in Fig. 8.) As also seen in this figure, 90 from this same ignition-chamber B' leads an exhaust pipe or passage B⁴, closed by a valve B⁵. The ignition is to be accomplished, as here illustrated, by means of a tube B⁶, closed at its outer end and having communication 95 at its inner end with the interior of the ignition-chamber B' through a passage b, which is intercepted by a slide-valve B⁷, the tube B⁶ being heated to a temperature suited to ignite its contents by means of a flame burning in 100 constant contact therewith within the chimney or housing b' in the usual manner. Other

modes of igniting the explosive compound within the chamber B' may, if desired, be employed.

The ignition-valve B⁷ is reciprocated so as to open the tube B⁶ into communication with the ignition-chamber B' at every other stroke of the engine, and for this purpose said valve B⁷ is controlled through the medium of a cam sprocket-wheel D of twice the diameter of the sprocket-wheel C', which is secured to the crank-shaft C, D' being a sprocket-chain driving the cam-wheel D from the crank-shaft. The cam-wheel D is provided with a segmental rib or cam d on its vertical side face, as well illustrated in Figs. 1, 2, 3, and 4. This cam d acts upon the valve B⁷ through the medium of a rock-shaft D², having an arm d' at one end carrying a friction-roller d³ at its free extremity, which bears on the side face of said cam d under the pressure of a spring d⁴. At its opposite end the rock-shaft D² is provided with an arm d⁵, to the upper end of which is pivoted a connecting-rod D⁶, which is in turn pivoted to a stud b³, projecting from the slide-valve B⁷ through a slot b⁵ in the plate B⁸, covering the same.

The air-inlet pipe B² is open at its end b¹, Figs. 1 and 3, to the external air, and between said open end and its connection with the ignition-chamber B' it is desirably provided with a check-valve b⁶, Fig. 3, in addition to the valve B³, (seen in Fig. 8,) and it is also provided with an enlargement B⁹, Figs. 1, 2, and 3, which is filled with fine wire or other porous material. The lowermost section of said pipe B² is also stuffed with similar material; but between said lowermost section and the stuffed or packed enlargement B⁹ is a section b⁶, which is desirably without stuffing or packing, and with this unpacked section b⁶ connects the induction-pipe e, which leads from the gasoline-pump E. Liquid injected by the pump into the air-induction pipe B² is distributed over the surface of the wires or other packed material employed in said pipe B² in its passage through the same with the air as the latter is drawn into the rear end of the cylinder B, and by means of such distribution it is more thoroughly vaporized and more perfectly combined with the air in adaptation for the better ignition or explosion of the compound which such vapor forms with the air as it enters said ignition-chamber. The pipe leading to the gasoline-pump E from any suitable source of supply is illustrated in Fig. 3 at e', where it is provided with a check-valve e¹³ of any suitable construction. The pump E is shown in longitudinal section in Fig. 6, wherein it is illustrated as being formed of a cylinder or body having a longitudinal bore or chamber e², extending about half its length, and a smaller bore e³ in continuation of e², and extending for the remainder of the length of the body. Within the smaller bore e³ slides a piston-rod e⁴, provided with a head e⁵, fitted to the larger bore e² and adapted to seat closely against

the shoulder e⁶ at the inner extremity of said larger bore or chamber e². The inlet-pipe e' for gasoline enters the chamber e² between the piston e⁵ and the outer end of the pump-body, as indicated in said Fig. 6. The outlet-pipe e from the pump leads from the smaller bore e³ near its inner end through a small orifice e⁷, which is closed by a light spring-valve e⁸. Between the head or piston e⁵ and the cap e⁹, which closes the outer end of the chamber e², is placed an expanding spring e¹⁰, operating normally to press the head e⁵ against its seat or the shoulder e⁶. The opposite end of the pump is closed by a cap e¹¹, having a hole through it for the piston-rod e⁴, and inclosing a suitable packing through which said rod may closely run. Said piston-rod e⁴ is reduced in diameter for a short distance adjacent to the head e⁵, and the margin of said head is notched, as indicated in Fig. 6, to give passage for liquid from one side to the other thereof when it is moved away from its seat e⁶.

The pump, when used for introducing a volatile liquid into the air-pipe B², is operated, as here shown, by means of a cam D¹, Fig. 4, on the continuously-rotating shaft which carries the cam sprocket-wheel D. The medium through which the cam D¹ is shown as acting upon the pump consists of a rock-shaft F, having an arm f provided with a wheel f', which is engaged by the cam D¹, and a second arm f², to which is pivotally and adjustably connected the rod f³. Said rod f³ has its outer end bent at right angles with its body, as indicated in Figs. 2 and 3, and near its extremity is provided with a hole through which projects the end of the piston rod e⁴ of the pump. Said piston-rod is provided with an adjustable collar e¹², forming a shoulder against which the laterally-bent end of the rod f³ may bear to press the piston-rod inward against the force of the spring e¹⁰, and thus open communication between the chamber e² and the chamber e³ of the pump, and at the same time by displacement force a small quantity of the liquid in the chamber e² out through the orifice e⁷ and into the air-induction pipe B². The oscillation of the rock-shaft F by the action of the cam D¹ vibrates the arm f², and thus reciprocates the rod f³, which in turn operates the piston of the pump, as described.

It is the intention that the liquid-pump E shall not be operated when the engine has reached or exceeded its maximum desired speed, and to this end the pump is held out of action at such times by means of a catch-lever G, (seen best in two views in Figs. 4 and 5,) provided with a shoulder at g and vibrated by engagement with the sliding sleeve H, with which the centrifugal governor I, Fig. 2, engages, said sleeve being mounted loosely on the shaft II', which revolves the governor I through the medium of a sprocket-wheel H², engaged by the chain D'. To bring the shoulder g on this lever G into engagement with

the arm f , said arm f is provided with an extension f^4 , and the shoulder g on said lever G is in position to engage the upper surface of said extension f^4 when it is fully depressed by the cam D^4 . When the engine is running with its proper limit of speed, the governor I will hold the lever G back out of the path of said arm f^4 ; but when the speed has reached or exceeded its limit said lever will be brought forward, so that upon the descent of the arm f the latter will engage the shoulder g , and will thus be held in its lowermost position until the speed of the engine shall have diminished sufficiently to result in swinging the lever G out of engagement therewith. During this period of continued engagement of the arm f with the shoulder g the pump-piston will be held pushed inward, but the source of gasoline-supply being below the pump there will be no inflow of fluid through the pump to the air-pipe, and consequently no consumption of gasoline vapor and no production of an inflammable or vaporized compound within the engine-cylinder or its ignition-chamber.

The exhaust-pipe B^4 is to be kept open throughout the period of excessive speed of the engine, so that the working of the piston within the cylinder B during such period will be unattended by the compression of air and may draw in air from the exhaust instead of through the air and vapor pipe B^2 . To this end the valve B^5 in the exhaust-pipe B^4 is connected with or made to rest upon an arm F' , attached to the rock-shaft F , which, as already explained, is oscillated by the cam D^4 , and is held at one extreme of its oscillation by engagement of the extension f^4 of the arm f with the shoulder g of the lever G during the period of such excessive speed.

The stem b^7 of the valve B^5 is provided with a collar b^8 , and between this collar and the under surface of the elbow b^9 in the exhaust-pipe B^4 is inserted an expanding spring B^{10} , which serves to normally draw the valve B^5 downwardly upon its seat and also to depress the crank-arm F' on the shaft F , and to thereby rock said shaft F in the opposite direction from that in which it is rocked or oscillated by the cam D^4 . The utilization of this spring in the oscillation of the shaft F is only a matter of convenience and any other spring or a spring applied at any other suitable point in the structure may be made to serve the same purpose.

The details of construction in the ignition-valve B^7 and in several other parts of the engine are the same essentially as set forth in a former application filed by me—to wit, Serial No. 342,582, filed March 4, 1890—and the same need not be here particularly described.

Having described the construction and operation of the engine as adapted for the use of a volatile liquid as the source of inflammable vapor, I will next describe the modifications shown in Figs. 9 and 10, by which a

gas under constant pressure may be employed instead of the vapor of such volatile liquid.

In the foregoing description it will be observed that the pump E is held open during the period of excessive speed, and that if a gas were supplied under pressure to the inlet of the pump it would, when the pump is thus held open, continually flow through the pump into the air-pipe B^2 . As a means of preventing this action in the use of gas, I provide for an independent operation of the pump or valve-actuating rod f^3 by pivoting it to a vibrating arm J , not connected with the shaft F , instead of to an arm attached to said shaft, and I vibrate said arm or lever J by means of an additional cam D^5 , attached to the same shaft which carries the cam D^4 . In this construction I give to the connecting-rod f^3 the laterally-bent form indicated at f^1 in Fig. 10, and opposite the bend thereof attach thereto a similarly-bent projection or arm f^5 . Within the space inclosed between the arm f^3 and the arm f^5 (forming in fact a cam-groove) projects an arm f^6 , attached to the shaft F in place of the arm f^2 in the construction previously described. This arm f^6 being rigid will upon the vibration of the rock-shaft F throw the adjacent end of the lever f^3 to one side of its normal position by reason of the bend or offset therein, and when this is done the vibrating arm J (which is loosely pivoted to a support suitable for the purpose) will be forced out of the path of the cam D^5 , so that when the pump is stopped it will be closed instead of open, as in the construction previously described. When the engine is at its excessive speed, the arm f^6 will be thrown forward or to the right and will bear against the offset portion of the rod f^3 , and will thus hold the arm J , to which said rod f^3 is pivoted, out of the path of the cam D^5 so long as said arm f^6 remains in this position, or, in other words, so long as the catch-lever G retains its connection with the extension f^4 of the arm f . This action, as explained, continues during the excessive speed of the engine and terminates when the speed of the engine has been reduced to its proper limit. The cam D^5 is arranged in this construction opposite or nearly opposite the cam D^4 , in order that when the speed of the engine is within its proper limits said cam D^5 may strike and actuate the lever J , and thus open the pump-valve for the inlet of gas when the arm f^6 is in its retracted position, as shown in Figs. 9 and 10, and when therefore the arm J will stand in the path of said cam.

The construction just described may be employed in connection with the use of a volatile liquid instead of gas; but I prefer, when gasoline is used, to employ the construction previously described as being the simpler.

The operation of the engine is obvious from the foregoing description. In starting it the first out and in strokes will be produced by hand or other external power applied to

the fly-wheel or otherwise. Upon the first outstroke the piston acts as a pump and draws the mixture of gas or gasoline vapor and air into the cylinder, and on the first 5 instroke this mixture is compressed, and at the completion of the instroke or at the point of maximum compression the ignition-valve is opened and the mixed vapor or gas and air is ignited, producing the required explosion 10 and the consequent impulse against the piston. At the extremity of the outstroke thus produced the exhaust-valve is opened, so that on the next return or instroke of the piston the contents of the cylinder are expelled 15 through the exhaust-port. The engine is now running by its own power, and at the completion of this instroke, thus expelling the contents of the cylinder, the exhaust-port is closed and the piston on its outstroke acts 20 again as a pump, drawing air and vapor or gas into the space behind the piston preparatory to its compression upon the following instroke and its ignition at the completion of said instroke, as before described.

25 By the construction above explained it will be observed that the exhaust-port is held open by the governor whenever and so long as the speed of the engine continues above its assigned limit, and during this period the re- 30 turn or in strokes of the piston are not accompanied by compression of the contents of the cylinder, because said contents have free egress and ingress through the continu- 35 ously-open exhaust-port. External air having such free ingress through the exhaust-port, the outward movements of the piston do not draw air through the gas and air pipe, and there is therefore no waste of vapor during the period of maximum engine-speed. As soon 40 as the speed of the engine falls to its proper limit, however, as indicated by the governor, the exhaust-port is closed by said governor, and upon the next instroke of the piston the combustible mixture is drawn through the 45 pipe B² and compression, ignition, explosion, and impulse again follow and are repeated upon alternate strokes of the piston until the speed shall again exceed its proper limit.

It is manifest that by the avoidance of air- 50 compression during the period of excessive speed as a result of keeping the exhaust-port open during such period much power is saved, and it is also evident that by avoiding the indraft of vapor-charged air, as described, 55 the utmost economy of material is also effected.

I claim as my invention—

1. In a gas-engine having the exhaust-port controlled by the governor and having a gasoline-pump for supplying vapor to the air-inlet pipe, the combination, with the governor and the air-inlet pipe, of pump-driving mechanism adapted to be thrown out of action by the governor, whereby the pump may be held out of operation during the period of excessive speed.

2. The combination, with the crank-shaft provided with a sprocket-wheel and the ignition-valve, of a sprocket-wheel of twice the diameter of that upon the crank-shaft, a 70 cam on said sprocket-wheel, and intermediate mechanism actuated by the cam and connected with the ignition-valve, said cam being adapted to give a quick motion to the ignition-valve in opening and closing the latter, 75 with a period of rest between its successive movements.

3. The combination, with the cam sprocket-wheel D, of the rock-shaft provided with arms d' and D³, respectively engaging the cam and the ignition-valve.

4. The combination, with the gasoline-pump and the fly-wheel, of a rotating cam, a rock-shaft provided with an arm for engaging the cam and also with an arm for operating the 85 pump, a vibratory lever provided with a catch engaging the first-mentioned arm of the rock-shaft, and the governor arranged to vibrate the lever.

5. The combination of the rotating cam D⁴, 90 the rock-shaft F, provided with an arm f for engaging the cam and the arm f² for operating the pump, the vibratory lever G, provided with a catch engaging the arm f, and the governor arranged to vibrate the lever G, 95 substantially as described.

6. In combination with the rock-shaft F, operated from the driving-shaft of the engine and provided with an arm f², and with a pump E for injecting liquid into the air-induction pipe, a rod f³, connected with the pump-piston and adjustably connected with the arm f², substantially as described.

In testimony that I claim the foregoing as my invention I affix my signature in presence 105 of two witnesses.

GEORGE W. LEWIS.
